UNITED STATES PATENT OFFICE.

NILS H. ANDERSON, OF BRIDGEPORT, CONNECTICUT, ASSIGNOR TO GERHARD F. DROUVE, OF BRIDGEPORT, CONNECTICUT.

WINDOW-OPERATING DEVICE.

1,254,959.

Specification of Letters Patent. Patented Jan. 29, 1918.

Application filed April 24, 1917. Serial No. 164,113.

To all whom it may concern:

Be it known that I, NILS H. ANDERSON, a citizen of the United States, residing at Bridgeport, in the county of Fairfield and 5 State of Connecticut, have invented certain new and useful Improvements in Window-Operating Devices; and I do hereby declare the following to be a full, clear, and exact 10 description of the invention, such as will enable others skilled in the art to which it appertains to make and use the same.

My invention relates to window operating devices, and has for its object such a construction and arrangement of the operative 15 elements that it will best effect an easy movement free from all tendency to bind or cramp. My invention further consists in efficient means for securely locking the closed window or windows to the sill:

20 Referring to the drawings:

Figure 1 represents a broken front elevation of the window frame and two of the windows, also broken view of the actuating rod;

25 Fig. 2 is an enlarged upper plan view of the operating levers in a closed position, broken view of the actuating rod and broken sectional view of one of the windows;

30 Fig. 3 is a similar view showing the position of the levers at the moment of the opening of the windows;

Fig. 4 is an enlarged view partly in section on line 4—4 of Fig. 2, showing a closed 35 window;

Fig. 5 is an enlarged broken view of the end of one of the operating levers showing the means located thereon for locking the window;

40 Fig. 6 is an enlarged broken upper plan view of the operating levers in full open position, broken view of the lower rail of the window, window sill and actuating rod;

Fig. 7 is an enlarged broken view of the 45 forked end of the sliding bolt carried by the window and enlarged broken view of the end of one of the operative levers connected thereto by a block to form a swivel joint;

Fig. 8 is an enlarged plan view of the 50 end of one of the operating levers, and a

horizontal central sectional view of the swivel block and its pin;

Fig. 9 is an enlarged view of a bracket carried by the actuating rod on line 9—9 of Fig. 6; and

Fig. 10 is an enlarged broken detail view of one of the operating levers.

As before mentioned, the principal object of my invention is to so construct and arrange the different elements adapted to 60 operate a series of windows with as little friction and consequent loss of power as possible, and to effect this result, it is necessary that the centers of all the moving parts to operate the windows be in line with 65 the center of the actuating rod, and in the same horizontal plane therewith when the windows are closed. The line of strain or applied power to operate the windows must necessarily pass through the center of the 70 actuating rod and the center of the operative elements connected therewith in order to avoid any tendency to cramp or bind.

The windows 1—2 and 3 represent part 75 of a line of windows adapted to swing on their pivots 4 through the medium of the longitudinally actuating rod 5 and the levers 6 and 7. Brackets, similar to 8, having antifriction rolls 9, are attached to the window sill 10 and support the rod 5 at intervals throughout the entire system. As the operative mechanism for each window is the same, and as only one operative mechanism is shown, a brief description of the 80 same will suffice.

The frame 11 carrying the antifriction rolls, is secured to the bracket 8 by screws 12, and 13 is a bracket secured to said frame which supports the sliding bolt 14 pivotally connected to the inner end of the 90 short lever 6. This lever is forked and embraces the central portion of the long lever 7 and is pivotally connected therewith by pin 15.

The outer end of lever 7 is pivotally supported to the sliding bolt 16 mounted in the bracket 17 secured to the angle iron 18, Fig. 4, secured to the lower rail 19 of the window. The inner end of the long lever 7 is pivotally connected to the rod 20 rota- 95 100

tably mounted in the bracket 21 adjustably secured to the actuating rod by U clamp 22.

It is important in order to secure a free and easy movement of the operative levers 5 that the pivotal connection of each end of the lever 7 and the inner end of the lever 6 should be in some form of a universal joint. These levers may be equipped with the universal joint shown in Figs. 7 and 8. 10 23 is a block adapted to have a horizontal movement on the pins 24, 24^a, 24^b, in the forked ends 25, 26, and 27 of the members 14, 16 and 20—see also Figs. 2 and 3. The 15 ends of the levers engaging these forked ends are each provided with the opening 28, Figs. 5 and 8, adapted to embrace the block with the lip 29 engaging with the groove 30 of the block as a fulcrum point in the vertical tilting movement of the levers.

20 The means provided for locking the window or windows in closed position consist of the angular plate 31, located near the outer end of the lever 7, and the pin 32 located on the sill 10. This plate is adapted to be adjusted, with respect to the position of the pin 25 and is then secured to the lever by the screws 33. In other words, the adjustable feature of the plate overcomes the difficulty of locating the exact position of the hole for the 30 pin were the plate immovably secured to the lever; as it is, the pin can be approximately located, and the plate adjusted to it.

To increase the bearing surface of the flat base of the bracket 21 on the rod 5, parts 35 34 of the stock are broken down to conform to the circular construction of the rod as shown in Figs. 6 and 9.

When the windows are closed, the position 40 of each set of levers opposite each window is in the position shown in Fig. 2. The movement of the actuating rod 5 in the direction of arrow *a* will cause the levers to move bodily in the same direction until the collar 35 and the shoulder of the forked 45 end 26 impinge against their respective brackets 13 and 17. This idle movement of the levers is solely for the purpose of releasing the locking plate from its engagement with the pin 32. The instant this is 50 done, the outward movement of the windows will begin by means of the pressure exerted against the beforementioned brackets, and this pressure will continue to the full window opening as shown in Fig. 6. All tendency 55 to bind or cramp in any of the moving parts is overcome by means of the novel arrangement and construction of the several operative elements, viz; the several centers of movement of these operative elements 60 being in the same horizontal plane with the central line of the actuating rod when the windows are closed, will not only facilitate an easy and frictionless starting movement to be maintained during the outward travel 65 of the windows by reason of the fact that the

centers of motion of the several operative members will substantially remain in line with the central line of the actuating rod during such outward movement. The centers 24, 24^a of the levers are always in line with each 70 other, as represented by line A, Fig. 6, and this line is always at right angles to the center line B, of the rod 5 in any and all positions occupied by the levers. The above arrangement and the result obtained thereby 75 could only be effected by locating the inner pivotal connections of the levers on a line with the central line of the actuating rod and between the rod and windows rather than on top or below the rod as uniformly 80 arranged in devices of this character.

Actuating the rod in a direction opposite to that required for opening the same will effect a closing movement greatly assisted by gravity, which will lose its force 85 when the windows have nearly assumed a vertical position, with the operating levers in the position shown in Fig. 3, when a further closing movement of the actuating rod will draw out the bolts 14 and 16 and cause 90 the angularly arranged plate 31 to engage the sill-pin 32, Fig. 2, and bring the windows firmly against the sill. When the windows are thus locked, the collar 36, on the bolt 14, will engage the bracket 13 and prevent 95 excessive strain being brought against the sill-pin.

Having thus described my invention, what I claim is:—

1. A window operating device comprising 100 an actuating rod, a long and short lever between the rod and window, one end of the long lever pivotally supported to a fixed member carried by the rod, the other end of said lever pivotally supported to a member movable parallel with the rod and mounted in a support carried by the window, the short lever pivotally supported by one end to the long lever and its opposite end to a member carried by a fixed support and also 105 movable parallel with the rod.

2. A window operating device comprising 110 an actuating rod, a long and short operating lever, the inner end of the long lever pivotally supported to a fixed member carried by 115 the rod, the opposite end of said lever pivotally supported to a member movable parallel with the rod and supported on the window, the short lever pivotally supported to the long lever and to a member movable 120 parallel with the rod and carried by a fixed support, and means carried by the long lever and located between its pivotal supports to engage means provided on the window sill for locking the window in closed position.

3. A window operating device comprising 125 an actuating rod, two operating levers between the rod and window, said levers pivot- 130 ed together, the inner end of one of the levers

pivotedly supported to a member carried by the rod, the outer end of said lever pivoted to a sliding member supported on the window, means carried by said lever adapted to engage means on the window sill for locking the window in closed position, the inner end of the other lever pivoted to a sliding mem-

ber mounted in a fixed support, the pivotal points of said levers connected with said sliding members being at right angles with the center line of the actuating rod in any of the positions occupied by said levers.

In testimony whereof I affix my signature.

NILS H. ANDERSON.
